APPAREL HOOK

Herbert H. Lahr, Evansville, Ind.

Application February 10, 1936, Serial No. 63,247

2 Claims. (Cl. 248—294)

This invention relates to apparel hangers and hooks and has more specific reference to a novel projectable and retractable spring controlled structure.

5 The need for a disappearing and concealed hook of this character is well recognized not only as a matter of convenience, but to promote safety and thereby avoid injury. I have, therefore, evolved and produced an arrangement which is 10 characterized by a sheath-like enclosure for a pivoted hook wherein the hook is partially projected under the action of a spring and automatically kept in an out-of-the-way retracted position when not in use.

15 By way of contrast with prior art structures, the invention relies for partial novelty on the provision of a suitable adapter casing susceptible of being attached to a wall or similar support, the hanger hook being pivoted in the lower portion thereof in such a way as to swing out to a substantially horizontal position for adequate article hanging purposes and when in the latter position being appropriately braced to promote strength and reliability.

20 25 The chief novelty, structurally speaking, has to do with the provision of a double acting spring confined within the adapter housing or casing wherein the spring serves to retain the hook in the casing in a novel trip manner and then operates to initially swing the hook out to a position to be easily grasped and swung down to supporting position.

Other features and advantages will become 30 more readily apparent from the following description and drawings.

35 In the drawings:

Figure 1 is a front view of the preferred embodiment of the invention showing the type wherein the sheath-like adapter casing is adapted to fit into a recess or mortise in a wall, board, or the like.

40 Figure 2 is an edge view of Figure 1.

Figure 3 is a horizontal section on the line 3—3 of Figure 2.

45 Figure 4 is a view in section and elevation showing the spring and control button means.

Figure 5 is an elevational view similar to Figure 2 showing how the supporting hook is swung out to apparel hanging position.

50 Figures 6 and 7 are perspective drawings of the spring and hook, respectively.

Figure 8 is a view of a different embodiment of the invention showing the attaching flange on the back of the casing with the casing projecting beyond the flange, which type of device

is applicable by simple screws, nails, or the like, without requiring mortising.

Figure 9 is a view in section and elevation of the arrangement depicted in Figure 8.

Both embodiments of the invention are 5 generically the same, but will nevertheless be described separately so far as the adapter casings are concerned. The hook, spring means and button, however, are the same throughout and corresponding numerals are utilized in Figures 1 10 to 9, inclusive. Considering, however, Figures 1 to 7 as a matter of convenience, it will be observed that the sheath-like adapter casing, which is of general rectangular form and vertically elongated, is denoted by the numeral 11. This 15 is of any appropriate material and open on its front and provided on the front with a facing as well as attaching flange or plate 12. In this form of the invention the casing is adapted to be set into a recess or mortised in a wall, door 20 frame, or the like.

The apparel supporting hook or arm is denoted 25 by the numeral 13. It is of appropriate proportion to fit in the casing so that it can be swung in and out in an obvious manner. It is pivotally mounted adjacent the bottom of the casing as indicated at 14 and is here provided with a stop element or abutment 15 which engages with the back wall of the casing when it swings out to a horizontal supporting position. This is to distribute the stress and strain and to provide an adequate retention brace for the hook arm as it swings out to its horizontal supporting position. It will be observed that the free end of the hook 30 is formed with a rounded head 16. This head is 35 adapted to cooperate with a keeper element 16^a on the upper end of a spring 17. The intermediate portion 19 of the spring is attached by a rivet or the like 20 to the back wall of the casing. The return bent end 21 which forms the lower 40 portion of the spring constitutes a presser and projecting element and is engageable with the hook 13 as shown in Figure 4 when it is swung into the casing.

45 It is to be observed that the upper portion of the front plate is constructed to accommodate a push button 22 whose inner or headed end is fastened to the keeper element 16^a. It will be apparent that when the button 22 is pushed inwardly, the hook 13 will be moved inwardly until the top portion thereof clears the keeper element 50 55 16^a. The hook 13 is then moved into operative position by the spring portion 21, said portion 21 having been tensioned by the previous move-

ment of the hook 13 into engagement with the keeper element 16a.

It is to be observed that at its front and adjacent the bottom the casing is fashioned with an abutment or stop element 23 which cooperates with the adjacent regulating abutment 15. Also, the rounded projected head on the free end of the hook 13 is so formulated as to function as a cam. That is to say, the rounded surface there-
of when the hook is swung in against the keeper element lifts the keeper element up and permits the latch action to be successfully accomplished.

It is understood that in this form of the invention the casing is adapted to be set into a recess or mortice in the relatively fixed supporting surface, such as a wall, frame, bed post, or the like. It is also understood that since the device is adapted for general home use, it is not always possible for the average person to successfully install the type of device illustrated in Figures 1 and 2 for example. Under the circumstances I provide the reversed arrangement depicted in Figures 8 and 9. Here the principle of construction and operation is the same. The adapter bracket or fixture, however, is denoted by the numeral 24 and comprises a base or attaching plate 25 which may be secured by fasteners, such as screws or nails 26. Here the sheath-like casing 27 is fastened to the plate so that it projects out beyond the plate. Consequently, instead of morticing the device into place flush with the wall, we simply attach the base plate to the wall and allow the casing to project slightly beyond the wall. Otherwise the features are the same and the same numerals are applicable to corresponding parts.

In both forms of the invention it is evident that we have a protector housing, casing, or suitable fixture, which constitutes the relatively fixed attaching means. This is adapted to receive and conceal the projectable and retractable pivotally mounted hook. The hook is itself so made as to facilitate hanging of garments and apparel thereon when in an extended supporting position. The hook is provided at its lower end with a stop abutment 15, which limits the inward swinging of the hook into the casing. The chief novelty, however, is in the cam latch

and keeper arrangement at the top comprising the features 16 and 16a, in conjunction with the finger actuated pressure button 22 and the spring means 18. Equal importance, however, is attached to the use of the single double acting spring 17 which includes the lower portion 21 calculated to initially start the hook out to be swung out from the casing when the releasing button is pushed in.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

1. A device of the class described comprising essentially an upright casing open at its front, a hook pivotally connected adjacent to its lower end to the casing and having at its upper end a head, and an upright spring strip arranged in the casing back of the hook and having a forwardly curved upper portion on which is a keeper element complementary to the hook head, and on which is also a forwardly projecting button.

2. A device of the class described comprising essentially an upright casing open at its front, a hook pivotally connected adjacent to its lower end to the casing and arranged in upright position in the casing and having a head at its upper end, and an upright spring strip having an intermediate portion mounted in the casing back of the hook and also having at its upper end an outwardly curved portion equipped with a button projecting in front of the casing and also equipped with a keeper element, the latter to engage the hook head and normally retain the hook against outward movement, said spring strip further having an outwardly curved lower portion arranged in the casing back of the hook and adapted on release of the hook head to press the hook outwardly.

HERBERT H. LAHR.
